UNITED STATES PATENT OFFICE.

JESSE MINOR, OF PITTSBURG, PENNSYLVANIA.

EXERCISING-BALL.

SPECIFICATION forming part of Letters Patent No. 777,478, dated December 13, 1904.

Application filed November 25, 1901. Serial No. 83,577. (No model.)

To all whom it may concern:

Be it known that I, JESSE MINOR, a citizen of the United States of America, residing at Pittsburg, in the county of Allegheny and State of Pennsylvania, have invented certain new and useful Improvements in Exercising-Balls, of which the following is a specification, reference being had therein to the accompanying drawings.

10 This invention relates to certain new and useful improvements in exercising-balls, and has for its object the provision of novel means whereby a person can easily exercise with the ball alone, not requiring the assistance of a 15 partner to exercise with the ball.

Another object of the present invention is to provide a ball with one or more handles whereby it may be conveniently grasped and exercised for the development of all the 20 muscles of the body.

My invention further contemplates to construct a ball of the above-described class that will contain a number of weights that may be easily removed and others substituted for the 25 purpose of regulating the weight of the ball.

The present invention further contemplates to construct a ball that will be simple in its construction, strong, durable, and comparatively inexpensive to manufacture.

30 With the above and other objects in view the invention consists in the novel combination and arrangement of parts to be herein-after more fully described, and specifically pointed out in the claims.

35 In describing the invention in detail reference is had to the accompanying drawings, forming a part of this specification, and wherein like numerals of reference indicate corresponding parts throughout the several views, 40 in which—

Figure 1 is a side elevation of my improved exercising-ball. Fig. 2 is a central vertical sectional view thereof, taken on the line 2 2 of Fig. 1. Fig. 3 is a side elevation of one 45 of the springs that may be attached to the handles. Fig. 4 is a vertical sectional view of one of the weights. Fig. 5 is a top plan view of the same.

In the drawings the reference-numeral 1

represents the inner casing, which incloses the 50 spherical body 1^a and which may be composed of any suitable material, having formed therein graduated recesses 2 3 and 4 5, which extend inwardly and are seated in similar recesses formed in the body 1^a. In said recesses 55 on one side are secured lugs 6 and on the opposite side spring-pressed pins 7. The reference-numeral 8 represents weights which are of various sizes, said weights having formed on their upper faces recesses 9, forming 60 a central grip 10. The weights are held within the respective recesses 2, 3, 4, and 5 by placing them back of the lugs 6 and the spring-pressed pins 7, the latter being depressed to permit of the placing of the weights 65 in position. It will be observed that the weights may be readily removed when desired by depressing the pins 7 within their sockets.

The reference-numeral 11 represents the outer covering of the ball, which is preferably 70 provided with a band 12 secured thereto, said band carrying handles 14, which are attached at 15 to the band, or they may be attached to either the inner or outer parts and have interposed between the grip of the handle and 75 the securing-point springs 16. The handles 14 may be attached directly to the covering, if desired, or they may be attached to the band. These handles may be constructed with a spring 16, as shown, or the springs may be 80 dispensed with.

The reference-numeral 17 represents a door formed in the outer covering, which is hinged at 18 and may be suitably secured at 19 for the purpose of holding the outer weight in 85 position and securing the door to the cover. The door 17 conforms in contour to the spherical casing 1, of which it forms a part. Two doors are provided, one for each opening to the graduated recesses.

It will be seen that by this construction an exercising-ball may be easily handled and certain movements obtained that could not be accomplished with the devices that are spherical in form without handles.

The many other advantages obtained by the use of my improved exercising-ball will be readily apparent from the foregoing descrip-

tion, taken in connection with the accompanying drawings.

It will be noted that various changes may be made in the details of construction without departing from the general spirit of my invention.

Having fully described my invention, what I claim as new, and desire to secure by Letters Patent, is—

- 10 1. In combination, a spherical casing having graduated recesses in opposite sides thereof, adapted to receive weights, and means for holding said weights in the recesses while permitting their removal at will, substantially as described.
- 15 2. In combination, a substantially spherical body and a casing inclosing the same with recesses extending into the body, means for removably securing weights in said recesses, and an outer covering for the casing, substantially as described.
- 20 3. In combination, a substantially spherical body and a casing inclosing the body with graduated recesses extending therein on opposite sides of the body, to receive weights, means for securing said weights in position,

a covering for the casing, and handles, substantially as described.

4. In combination, a substantially spherical body, and a casing inclosing the body with 30 graduated recesses extending therein on opposite sides of the body to receive weights, and doors for inclosing the openings to said recesses, substantially as described.

5. In an exercising-ball, a body, a casing 35 provided with recesses to receive weights, a covering for the casing, and handles arranged at opposite sides of the body.

6. In an exercising-ball, the combination of a body, a band secured thereto, hand-grips, 40 and resilient connections between the said hand-grips and band.

7. The combination in an exercising-ball having a graduated recess, of means at each grade for securely holding a weight in a 45 grade.

In testimony whereof I affix my signature in the presence of two witnesses.

JESSE MINOR.
